Primary Examiner — Messina L Smith*Assistant Examiner* — Jennifer B Salazar(57) **CLAIM**

The ornamental design for a pet fence, as shown and described.

DESCRIPTION

FIG. 1 is a front, top, right perspective view of a pet fence, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear, bottom and left-side perspective view thereof;

FIG. 9 is an enlarged view of a portion of the pet fence shown in area 9 in FIG. 1; and,

FIG. 10 is an enlarged view of a portion of the pet fence shown in area 10 in FIG. 8.

The broken lines in the drawings depict portions of the pet fence that form no part of the claimed design. The dot-dash broken lines encircling portions of the pet fence in FIGS. 1 and 8 and illustrated in enlarged views in FIGS. 9 and 10 form no part of the claimed design.
